UNITED STATES PATENT OFFICE.

HARRY CURRIER, OF MADISON, MAINE, ASSIGNOR OF TWO-THIRDS TO JOHN A. HAMILTON AND JOHN W. STOBIE, BOTH OF MADISON, MAINE.

AUTOMATIC COUPLING FOR AIR-PIPES.

1,224,611.

Specification of Letters Patent.

Patented May 1, 1917.

Application filed June 15, 1916. Serial No. 103,783.

To all whom it may concern:

Be it known that I, HARRY CURRIER, a citizen of the United States, residing at Madison, in the county of Somerset and State of Maine, have invented certain new and useful Improvements in Automatic Couplings for Air-Pipes; and I do hereby declare the following to be a full, clear, and exact description of the invention, such as will enable others skilled in the art to which it appertains to make and use the same.

This invention relates to improvements in automatic couplers for train pipes, and has for its object to provide mating train pipe coupling elements that will automatically couple simultaneously with the coupling of the cars together and will remain engaged until the cars are subsequently uncoupled.

Another object is the provision of means of movably supporting the coupler beneath the drawhead of the car, so as to permit independent movement of the coupler and drawhead.

With these and other objects in view, the invention consists in the novel construction, combination and arrangement of parts as will be hereinafter specifically described, claimed and illustrated in the accompanying drawings, in which:

Figure 1 represents a fragmentary side elevation of two coupled cars, illustrating two of the coupling elements in engagement with each other;

Fig. 2 represents a longitudinal sectional view through one of the coupling elements;

Fig. 3 represents a fragmentary bottom plan view of the car;

Fig. 4 represents a vertical sectional view on the line 4-4 of Fig. 2, and

Fig. 5 represents an elevation of one of the coupling elements.

The two mating coupling elements are identically constructed, and as a description of one applies equally well to the other, I will describe the construction of one in detail.

Referring to the drawings in detail, wherein similar reference numerals designate corresponding parts throughout the several views, the numeral 8 indicates a cylinder carrying integral vertical trunnions 9, pivotally supported in a substantially rectangular frame 10 suspended below the drawhead 11 of the car body, whereby the cylinder may oscillate on a vertical axis in-

dependently of the drawhead. The cylinder 8 is normally retained in parallel relation to the drawhead by a pair of springs 12 connected at one end to the inner extremity of the cylinder 8 and at their opposite ends to the supporting frame 10.

Heads 13 and 14 are fitted in the inner and outer ends, respectively, of the cylinder 8, and the inner head slidably receives a pipe section 15 connected with a coupling 16, which latter is connected with a flexible tube 17, whereby air is conducted from the train pipe 18 to the pipe section 15. A preferred type of rotary valve 19 is connected with the train pipe 18 for controlling the passage of air to the coupling element and is operable by longitudinally movable rods 20, having pivotal connection at their terminals with the valve 19 and having angularly directed outer terminals 21 arranged adjacent the sides of the car, whereby they may be conveniently actuated.

A pipe section 22 is slidably mounted in the outer head 14, and is formed integral with the piston 23 reciprocably mounted within the cylinder 8 and having an axial opening communicating with the pipe section 22 and receiving the adjacent terminal of the pipe section 15.

The outer terminal of the pipe section 22 is connected with the coupling head 25, having the axial opening 26 therethrough communicating with the pipe section 22. A cushion or gasket 28 is fitted in recesses formed in the outer terminal of the coupling head 25 and is adapted to engage a corresponding gasket carried by the coupling element of the adjacent railway car to present an air tight joint between the coupling heads of the mating coupling elements.

The coupling head 25, pipe sections 22 and 15 and piston 23 are normally retained in outwardly extended position with relation to the cylinder 8 by the tension of a coil spring 29, arranged within the cylinder 8 and engaged at one end with the inner head 13 and at the opposite end with the piston 23, and the piston is prevented from turning within the cylinder by longitudinal ribs 30 formed thereon and slidably engaged in diametrically opposed and internal grooves 31 formed in the wall of the bore of the cylinder.

A pair of diametrically opposed spring retaining members 32 are rigidly connected

with each coupling head 25 and are provided with inwardly directed teeth 33 adapted to engage behind the inclined shoulder 34 of the adjacent coupling head to retain the heads in coupled position. The inclined surface 34 forms one wall of a circular groove formed in the coupling head in which the inwardly directed teeth or lugs 33 of the spring retaining members are received, and the outer surfaces of the heads outwardly of the grooves are tapered or inclined, as indicated at 35, so as to spread the spring retaining members as the coupling heads move together.

15. What I claim is:

1. The combination with a railway car including a body and drawhead, a frame carried by said drawhead, a cylinder pivotally supported on a vertical axis in said frame, means normally retaining said cylinder in parallel relation to said drawhead, pipe sections slidably mounted in said cylinder, means normally retaining said pipe sections in outwardly extended position, a coupling head carried by one of said pipe sections, and a pair of spring retaining members carried by said coupling head.

2. The combination with a railway car including a body, a drawhead, and a train pipe, of a supporting frame carried by said drawhead, a cylinder pivotally mounted on a vertical axis in said frame, means normally retaining said cylinder in parallel relation to said drawhead, connected pipe sections reciprocably mounted in said cylinder, means normally retaining said pipe sections in outwardly extended position, a flexible tube

connecting the inner terminal of said pipe sections with said train pipe, a coupling head carried by the outer terminal of said pipe sections, and a pair of spring retaining members carried by said coupling head.

3. In an automatic coupling for air pipes, a cylinder, a piston reciprocably mounted in said cylinder, means normally retaining said piston extended toward one end of said cylinder, pipe sections connected with said piston, a hollow coupling head connected with one of said pipe sections having an external groove provided with an inclined wall, and a pair of toothed spring retaining members carried by said coupling head.

4. The combination with a railway car including a body and drawhead, a cylinder pivotally supported on a vertical axis by said drawhead, spring means normally retaining the cylinder in parallel relation to the drawhead, and a coupling head supported by said cylinder.

5. The combination with a railway car including a body and drawhead, a frame carried by said drawhead, a cylinder pivotally supported on a vertical axis in said frame, means normally retaining said cylinder in parallel relation to said drawhead, and a coupling head slidably supported by said cylinder.

In testimony whereof I affix my signature in presence of two witnesses.

HARRY CURRIER.
